(57) **CLAIM**

The ornamental design for a wrist-worn electronic device, as shown and described.

DESCRIPTION

FIG. 1 is a perspective view of a wrist-worn electronic device.

FIG. 2 is a left elevational view of the wrist-worn electronic device of FIG. 1.

FIG. 3 is a right elevational view of the wrist-worn electronic device of FIG. 1.

FIG. 4 is a top plan view of the wrist-worn electronic device of FIG. 1.

FIG. 5 is a bottom plan view of the wrist-worn electronic device of FIG. 1.

FIG. 6 is a front elevational view of the wrist-worn electronic device of FIG. 1; and,

FIG. 7 is a rear elevational view of the wrist-worn electronic device of FIG. 1.

The evenly dashed lines in the drawings depict portions of the wrist-worn electronic device that form no part of the claimed design. The dot-dash broken lines depict the bounds of the claimed design and form no part thereof.
